CALEB A. SUNDEEN, OF GARDNER, MASSACHUSETTS, ASSIGNOR TO ICEBERG MANUFACTURING COMPANY, A CORPORATION OF MASSACHUSETTS

SEALING RING

Application filed November 3, 1928. Serial No. 317,016.

My invention relates to a closure member adapted to effect a tight seal of a container and more particularly to a sealing ring adapted for use with cabinets for water coolers of the inverted bottle type.

5 My invention will be described as applied to a water cooler wherein a container is surrounded by a cooling agent and water is fed thereinto from an inverted bottle that is supported on the container. However, it will be understood that my improved ring may 10 be applicable to other liquid and beverage coolers, as well as to other fields where it is desirable to effect a closure seal for various purposes.

15 It is one object of my invention to provide in a cooler of the above described character a structure of sealing ring which will effectively close and seal the insulated space containing the cooling agent so as to prevent 20 heat losses at the point where the water bottle is supported.

It is another object of my invention to provide a sealing ring of the character described 25 and of such construction that the weight of the water bottle will cooperate in the sealing.

It is a further object of my invention to provide a construction of ring and an arrangement of parts whereby the ring is 30 mounted externally of the cabinet and associated water container and to provide such ring with means that will insure the maintaining thereof in position on the cabinet.

Other and further objects of my invention 35 will be apparent from the following specification and the accompanying drawings, wherein—

Figure 1 is a top plan view of my improved sealing ring;

40 Fig. 2 is a partial sectional view of a water cooler cabinet showing my sealing ring in position thereon and in vertical section and also indicating the inverted water bottle in position, the parts being broken 45 away where unnecessary to the illustration of my invention;

Fig. 3 is a vertical section of a portion of a modified form of sealing ring; and

50 Fig. 4 is a vertical section of a portion of another modified form of sealing ring.

Referring to Fig. 2, 11 indicates the outer wall of a cabinet or chamber, 12 indicates the inner wall thereof, and 13 indicates cork or other insulation therebetween. These elements surround a chamber 14 that may be designated as the cooling chamber since it is intended to be and normally receives ice for cooling purposes or, more preferably, either the cooling coil or the brine tank of any of the well known types of electrically operated mechanical refrigeration systems.

The cooling chamber may be part of a complete cabinet, or supported on a stand, or merely have a base of its own, it being immaterial to the present invention how this cooling chamber is mounted.

Mounted interiorly of the chamber 14 and surrounded thereby is a water container 15 which may be of sheet metal, glass, crockery or any desired material. The cabinet or chamber has an opening through its top as indicated at 16, through which the upper end of the water container 15 projects and into which the mouth of the inverted bottle or other water vessel 17 is adapted to be introduced.

It is highly desirable to prevent any heat losses from the chamber 14 regardless of the cooling agent therein, and to this end, the chamber is surrounded by the insulated walls 13 except for the opening 16. In order to prevent heat losses by transmission it is necessary to insulate any contact between the water container and the cabinet and this is preferably done by spacing the two apart 50 as illustrated in Fig. 2. However, such a space must be sealed if heat losses there-through are to be prevented.

I propose to provide a sealing ring 18 of particular and especial construction and advantage for this purpose. The ring has a bottom consisting of a flat, annular portion 19 terminating at its inner edge at the opening 21, through which the neck of the bottle 17 projects, and terminating at its outer edge in an inclined downwardly projecting lip 22. The edge 23 of the lip is formed by the acute angle between the inclined portion of lip 22 and the termination of the outer side wall 24. In my ring, I have illus- 100

trated the side wall 24 as arcuate but this need not necessarily be the contour thereof.

The side wall 24, at its upper edge, joins a downwardly sloping wall 25 which extends inwardly to the opening 21 and there terminates in the vertical wall 26. As shown, the contour of the sloping wall 25 is such as to coincide with the shape of the standard bottle used in inverted water bottle coolers, well known in this art, when the bottle is in position. However, either the wall 25 can be of any other contour when used with other types of liquid vessels or the liquid vessel may effect a seal between the vessel and the ring at the edge 27 which forms the juncture between the side wall 24 and sloping wall 25.

In my improved ring, this edge 27 is especially located with respect to the lip 22 so that the weight of the water vessel received at that point will be properly distributed in the ring to force the edge 23 of the lip into tight engagement with the top of the cabinet 11. That is to say, by the pressure of the weight of the water vessel at the edge 27, the whole ring is compressed and this will result in a slight spreading of the ring with the resultant tendency to force the edge 23 outwardly. The edge 23 being an acute angle, in engagement with the top of the cabinet, tends to resist the spreading and thus to grip the top of the cabinet more firmly. This arrangement forms a very tight seal between the top of the cabinet and the ring to prevent leakage through the opening 16 in the cabinet. In the form shown in Fig. 2, the weight of the bottle 17 will also bring the flat portion 19 of the ring into engagement with the top of the cabinet 11 where it overhangs the edge of the opening 16 to form a supplementary seal at that point. The location of the edge 27 may be defined as being between the outer circumference of the ring 18 and a vertical line intersecting the center of the body of the ring, i. e., between its inner and outer edges.

In order that water may flow into the container 15 from the bottle 17 as needed, the ring is provided with an air vent 28 which is a groove extending across the face of the sloping wall 25 from the inner aperture 21 to the edge 27.

To further insure the ring remaining in position and effecting a good seal, it is provided with an annular slot 29 in which the upper edge of the container 15 is adapted to fit. As shown in Fig. 2, the upper edge of the water container is straight, but it will be understood that any other form of edge could be used and the slot 29 shaped to cooperate therewith. By fitting the ring 18 on the top of the container 15 it is held more securely in place at the time of inserting the bottle in the container and also a tight seal is ef-

fected for the compartment 14 where the ring contacts with the top of the container.

In Fig. 3 is shown a modified form of ring, which has a bottom wall 31, arcuate side wall 32, sloping upper wall 33 and inner wall 34 joining each other in the same arrangement and proportions as described above except, in place of the lip 22 that there adjoins the bottom and outer walls, this form shown in Fig. 3 is provided with an annular groove 35 near the outer wall 32 which leaves a lip 36 between it and the outer wall 32. The proportionate weight distribution is the same as described above in connection with Figs. 1 and 2, but the tendency for spreading will occur more in the portion on the inside of the groove 35 so that the lip 36 will merely be forced outwardly without elevating it away from the top of the cabinet with which it is in engagement. The ring is also provided with the slot 37 for receiving the upper edge of the water container or crock and corresponding to slot 29 in Fig. 2.

In the form shown in Fig. 4, the ring is provided with a bottom wall 41, outer wall 42, sloping upper wall 43 and inner wall 44, joined together in the same arrangement as described above in connection with Figs. 1 and 2 except, the bottom wall has a plurality of V-shaped grooves 45 therein, the curves joining each other so as to provide at their intersecting edges 46 along the bottom of the ring and terminating in a sharp edge or lip 47 where the bottom wall joins the side wall 42. Again the weight distribution as referred to above in Fig. 2 will force the sharp edge 47 and one or more of the sharp edges 46 into tight engagement with the top of the cabinet 11 so as to effect the tight seal that is desired at this point, as described above.

Modifications may be made in the arrangement and location of parts within the spirit and scope of my invention, and such modifications are intended to be covered by the appended claims.

I claim:

1. A sealing ring comprising a bottom wall having a lip at its outer edge, an outer wall and a sloping top wall, the point of juncture between the outer and top walls occurring between the outer edge and the vertical center line of the body of the ring.

2. A sealing ring comprising a bottom wall having a lip at its outer edge, an outer wall, a sloping top wall, the point of juncture between the outer and top walls occurring between the outer edge and the vertical center line of the body of the ring, an air vent in the body of the ring and means for positioning the ring upon the container to be sealed.

3. A sealing ring having a flat bottom wall, an arcuate outer wall, an inclined lip joining the bottom and outer walls, a sloping upper wall, an inner wall, an air vent in the

sloping wall between the outer and inner walls, and a guiding and positioning groove in the body of the ring.

4. A sealing ring comprising a bottom surface having a lip adapted to rest upon a surface of a device to be sealed, and a sloping upper surface adapted to receive and support an object so that the weight thereof will tend to spread the ring laterally and thus 10 force the lip to tightly grip the surface upon which it is resting.

5. A cabinet comprising a cooling chamber having an open therein, a liquid container located in the cooling chamber, and a sealing 15 ring having a bottom surface terminating in a lip adapted to engage the top of the cabinet and to overlap said opening, said sealing ring also being adapted to receive and support a liquid container.

20 6. A cabinet comprising a cooling chamber having an opening therein, a liquid container located in the cooling chamber and accessible through said opening, a sealing ring having a bottom surface terminating in a lip adapted to engage the top of the cabinet and to overlap said opening, said sealing ring also being adapted to receive and support a liquid container, and a groove in the sealing ring adapted to cooperate with the projecting 25 portion of the liquid container.

7. A flexible sealing ring composed of insulating material and comprising a bottom surface having a lip adapted to rest upon a surface of a device to be sealed, and an upper 30 surface adapted to receive a weight which will tend to spread the ring laterally and force the edge of the lip to grip the surface upon which it is resting.

8. A sealing ring comprising a bottom surface having a depending portion adapted to engage a surface of a device to be sealed, and an upper surface adapted to receive the weight of an object so as to spread the ring laterally to force the bottom surface of the 45 ring into contact with the said surface which the depending portion is engaging.

9. A cabinet comprising a cooling chamber having an opening in one wall thereof, a liquid container located in the cooling chamber 50 and spaced from the sides of said opening, an inverted bottle adapted to rest upon and feed water into said container and a sealing ring interposed between the top of the container and the bottle and also bridging the 55 space between the container and the cooling chamber.

10. A cabinet comprising a cooling chamber having an opening in one wall thereof, a liquid container located in the cooling chamber 60 and spaced from the sides of said opening, an inverted bottle adapted to feed liquid into said container, and a sealing ring upon which the inverted bottle rests, said ring having a surface substantially conforming to the 65 surface of said bottle and effecting a seal at

the juncture of the inverted bottle and liquid container and also sealing the opening between the liquid container and cooling chamber, the pressure due to the weight of the inverted bottle being applied upon the ring 70 along a line passing between the liquid container and the outer edge of the ring.

11. A cabinet comprising a cooling chamber having an opening in one wall thereof, a liquid container located in the cooling chamber and spaced from the sides of said opening, an inverted bottle adapted to feed liquid into said container, and a rubber sealing ring upon which the inverted bottle rests, said ring having a surface substantially conforming to the 75 surface of said bottle and effecting a seal at the juncture of the inverted bottle and liquid container, said sealing ring also closing the opening between the liquid container and cooling chamber so as to prevent heat leakage 80 between the container and cooling chamber.

12. A sealing ring adapted to have a pressure applied thereupon when in operative position, said sealing ring comprising one surface having a lip engaging a cooperating surface for sealing purposes, the lipped surface being oppositely disposed to the place of applying pressure to the ring and the edge of the lip gripping said cooperating surface when pressure is applied. 95

13. A sealing ring comprising a bottom surface having a flat portion, an outer surface, a lip at the point of juncture between the bottom and outer surfaces and offset from the flat portion, and upper and inner surfaces 100 joining with the side and bottom surfaces respectively.

14. A cabinet comprising a cooling chamber having an opening in one wall thereof, a liquid container located in the cooling chamber and spaced from the wall of the opening and accessible through said opening, a second liquid container located above and communicating with the first-named liquid container and means for sealing the opening between 105 said container and the wall of the opening and also to seal the connection between said containers.

In testimony whereof I affix my signature. CALEB A. SUNDEEN. 115
